UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING MACHINE.

Application filed November 18, 1922. Serial No. 601,745.

My invention relates to mining machines and one of its objects is the provision of improved apparatus for cutting out sections from the mine wall, dividing such sections by an additional cutter, and removing the cut-out sections.

A further object of the invention is the provision of improved mechanism for cutting a horizontal kerf in the face of a mine 10 vein.

Another object of the invention is the provision of improved mechanism for breaking into smaller pieces sections of mineral cut out from the face of the veins.

More particularly it is the object of the present invention to combine with a loop-chain core cutter, a plane kerf cutter for cutting the core longitudinally to divide the same into smaller sections to facilitate the 20 removal thereof from the mine wall.

Other objects of the invention will appear hereinafter, the novel features and combinations being set forth in the appended claims.

Referring to the accompanying drawing, Figure 1 is a plan view of a complete mining and loading machine, with my improvements included therein.

Fig. 2 is a sectional elevational view of 30 the construction shown in Fig. 1.

Fig. 3 is an elevational view of the kerf-cutter for dividing the core longitudinally.

Fig. 4 is a plan view of the structure shown in Fig. 3, with certain portions in 35 sectional plan, to illustrate details of construction.

Fig. 5 is a section of Fig. 4 on the line 5—5 looking in the direction of the arrows.

Fig. 6 is an enlarged fragmentary section 40 elevation to illustrate the construction used for assembling the parts of the horizontal kerf cutter.

Fig. 7 is a fragmentary view showing the bit socket and the means for holding the 45 bit therein as applied to the horizontal kerf cutter;

Fig. 8 is a detail view showing the relation between the horizontal kerf-cutter and the abutment drum.

Fig. 9 is a detail of the ball bearing cage 50 for the horizontal kerf-cutter, and

Fig. 10 is a plan view of the structure shown in Fig. 9.

The mining and loading machine illustrated in the accompanying drawing may 55 be of the class illustrated in my Patent No. 1,325,031, granted Dec. 16, 1919, for an improvement in mining machines.

I wish it to be understood, however, that my improvements as defined by the claims 60 hereto appended may have a general application because they are applicable to other types of mining machines than the one shown in the aforesaid patent.

The mining machine shown in the accompanying drawings comprises a main frame 3 and a supplemental frame 4 which is pivoted to the main frame at 5 between the vertical standards 6. The main frame 3 may be mounted on skids 7, 7 on a mine floor, and 70 may be made of such weight, strength and material as will be suitable. The main frame is also provided with suitable roof jacks 8, 8, which are mounted at the upper ends of the standards 6. By means of these 75 roof jacks the main frame 3 may be firmly anchored in adjusted position in the mine, particularly to resist swinging of the main frame or rearward movement thereof.

The supplemental frame 4 comprises upper horizontally extending bracket arms and a lower horizontally extending platform, which serve to support the various parts of the automatic mechanism. A motor, preferably an electric motor, and shown diagrammatically at 9 in Fig. 1, is mounted on the rear end of the platform 10 at one side thereof. The pinion 11 on the shaft of electric motor 9 meshes with the gear 12 which is keyed to the transverse shaft 13, 90 the ends of which are mounted in bearings 14, 14 at the upper rear portion of the supplemental frame 4. At the central portion of the shaft 13 is a worm 15 meshing with the horizontal worm gear 16 shown in Fig. 2. 95

The worm gear 16 is mounted loosely on the upper end of the shaft 40 at the lower end of which is a sprocket 17 meshing with the sprocket chain 18. This sprocket chain is provided with a plurality of laterally extending flights 19, 19, which move over the upper surface of the platform 10. The sprocket chain flight conveyor 18, 19, is endless and its forward portion meshes with a sprocket wheel 20 mounted on a vertical 100 shaft between the platform 10 and the lower

end of the forward intermediate connecting frame 21, the upper end of which is connected by means of the stationary bearing 22 to the forward ends of the horizontal bracket arms 23 and 24. These bracket arms extend forwardly from the crosspiece 25 of the supplemental frame and join at their outer ends where the bearing 22 is located.

Mounted on the shaft of the sprocket wheel 20 so as to rotate therewith is a pinion 26 which meshes with a gear wheel 27 mounted on the intermediate frame 21 and provided with a worm 28 meshing with the worm wheel 29. The shaft 30 of the worm wheel 29 is also mounted on the intermediate frame 21 and carries a sprocket wheel 31 as shown in Fig. 2. It should be noted that Fig. 2 shows the loop chain core cutter in its central longitudinal position after being swung 90° from the position shown in Fig. 1. Fig. 2 shows all of the parts in side elevation when the chain cutter extends forward in central position.

Meshing with the sprocket wheel 31 is a sprocket chain 32 extending around the frame 33, which is provided with suitable guideways for said sprocket chain and is supported by the intermediate frame 21. The sprocket chain 32 is provided with cutters 34 extending laterally or axially relative to the cutter frame 33 as shown in Fig. 1.

The sprocket chain 32 may be tightened or loosened by means of the nuts 35 and 36 which are threaded on the screw-threaded rod 37 extending rearwardly from the central portion of the chain cutter frame 33. It should be observed, however, that the screw-threaded rod 37 is fixed to the rectangular block which extends from and is rigid with the frame 21. This block is provided with guide grooves along its upper and lower surfaces to receive the horizontal spaced apart bars at the rear portion of the cutter frame 33. Through the vertical cross piece at the rear end of the bar extends the screw-threaded rod 37 so that when the nut 35 is loosened and the nut 36 tightened, the cutter frame will be moved to the left either to make more slack in the chain or to permit the radial length of the cutter to be appreciably changed. If necessary a link may be removed in order to prevent the chain from becoming too slack when the desired change in the radial length or range of the cutter is obtained. By loosening the nut 36 and tightening the nut 35 the cutter frame may be moved outwardly relatively to the upright axis of rotation and thus slack may be taken out of the chain or the radial length increased. If desired, an extra link may be inserted in order to secure a proper increase in the cutting range without causing the chain to become too tight. After the desired adjustments have been made and one

or more links inserted or withdrawn, the nuts 35 and 36 are both tightened to hold the cutter frame firmly in adjusted position relative to the axial frame 21.

In order to control the operation of the chain cutter I have provided a clutch 38 which may be of any suitable or well known construction, provided with a groove 39 to be engaged by an operating lever. When the current to the electric motor 9 is turned on to rotate the motor in the proper direction, motion will be transmitted to the transverse shaft 13 and thence through the worm 15 and worm gear 16 to the vertical shaft 40, the upper end of which is journaled in the bearing 41 at the rear end of the horizontal bracket arm 42 attached to the cross piece 25 of the supplemental frame. The rotation of the vertical shaft 40 imparts motion to the sprocket 17 which in turn actuates the endless flight conveyor 18, 19 and imparts motion to the sprocket wheel 20, the pinion 26, the gear 27, the worm 28, the worm wheel 29, the sprocket wheel 31 and the chain cutter 32. The arrow 43 indicates the direction of movement of the flight conveyor, and the arrow 44 indicates the direction of movement of the chain cutter.

The entire chain cutter is also advanced laterally over approximately a semi-circular path during the cutting operation. The means for advancing the cutter chain laterally to secure arcuate feed thereof comprises a peripherally grooved wheel 45 connected to the upper end of the intermediate frame 21, so as to rotate therewith on the bearing 22 and on the bearing in the platform 10 provided for the sprocket wheel 20. To the wheel 45, at 46, is secured one end of a rope 47, the other end of which is secured to a grooved wheel 48, mounted on a vertical shaft 50 carrying the worm wheel 49. It should be observed, however, that the worm wheel 49 is mounted loosely on the shaft 50, and that a clutch 51 is provided for connecting the worm wheel 49 to the wheel 48, so as to transmit motion to the latter from the shaft 50. This may be done by suitable means engaging the groove 52 of the movable member of the clutch 51 in a well known manner. The upper end of the shaft 50 is journaled in the rear end of the bracket arm 23 and the lower end of the shaft 50 is journaled in the bracket arm 53, extending from a portion of the supplemental frame.

Meshing with the worm wheel 49 is a worm 54 on the transverse shaft 13. Therefore, when the electric motor 9 is operated in the proper direction, motion will be transmitted to the worm gear 49 so as to rotate the same in anti-clockwise direction. When the clutch 51 is thrown in, motion will be transmitted through the wheel 48, the rope 47, and the wheel 45, to the intermediate frame 21, thereby swinging the cutter frame

from right to left, looking forward or in an anti-clockwise direction when viewed in plan. Although I have shown a jaw clutch 51, any other suitable and well known clutch 5 may be used if desired. The same is true 5 with respect to the other clutches shown.

When the cutter frame 33 is in initial position, it is diametrically opposite the position shown in full lines in Fig. 1. The 10 chain cutter loops the section of material in which the kerfs were cut by the chain cutter 32, because the latter has an unobstructed core opening extending therethrough. When the chain cutter 32 is in 15 substantially central position, the shape of the section cut out would conform to the unobstructed core opening, when such chain cutter is used alone or without a dividing cutter.

20 The foregoing description applies to the structure shown in my aforesaid Patent No. 1,325,031, dated Dec. 16, 1919, which does not disclose a dividing cutter, hereafter described.

25 When a complete semicircle is made by the chain core cutter 32, the section of material cut out will be crescent shaped in plan view, as illustrated at 70, in Fig. 1. Inasmuch as this entire section of material cut out is too 30 large for the conveyor to handle, it is desirable to break up the same into smaller sections. In order to accomplish this result, I provide automatic locking mechanism for locking the cutter frame in its final position and connected to the cutter frame mechanism to exert a bending force on the crescent-shaped section at one end thereof to break up the same into smaller sections as indicated by the irregular dot and dash lines 35 56, 57 and 58. In order to lock the cutter frame against being retracted I provide on the upper surface of the wheel 45 a catch 59 which presents a vertical face toward the cutter frame and an inclined face in the opposite direction. Between the outer ends 40 of the bracket arms 23 and 24 is pivoted a latch lever 60 which will be lifted by the inclined surface of the catch 59 when the wheel 45 approaches the position shown in 45 full lines in Fig. 1. The latch bar 60 being pivoted to the supplemental frame at 61 is free to drop of its own weight when the catch 59 passes under and beyond the same. The vertical face of the catch 59 will then 50 engage the latch bar 60 and prevent the cutter frame from being retracted if it is attempted to do so. In some instances it may be desirable to continue the lateral advancing movement of the cutter frame and it is 55 therefore preferred to provide an additional catch 62 on the upper surface of the wheel 45, so that the cutter frame may be locked by the catch 62 engaging the latch bar 60. The catch 62 is also provided with an inclined surface over that portion which is

visible in plan view. Therefore, when the wheel 45 rotates a sufficient distance anti-clockwise the catches 59 and 62 will lift the latch bar 60, but when it is attempted to rotate the wheel 45 in a clock-wise direction 70 the latch bar 60 coacting with either the catch 62 or the catch 59 will act as a locking mechanism to prevent such return movement. The locking mechanism may be released, however, by lifting manually the 75 latch lever 60 a sufficient distance.

80 A flat rope or metal belt 64 is connected pivotally at 63 to the front end of the cutter frame 33 opposite the cutters 34. This rope or belt extends around the crescent-shaped mass of coal cut out from the mine wall by the loop chain core cutter 32, and thence toward the rear, where it is secured to the drum 65 mounted on the shaft 66, 85 bearings for which are provided on the platform 10 and in the cross piece 25. Loosely mounted on the vertical shaft 66 is a worm wheel 67 which meshes with the worm 68 on the transverse driving shaft 13. When the electric motor 9 is operated, motion will 90 be transmitted to the worm wheel 67 to rotate the same in an anti-clockwise direction. When the clutch 69 is thrown in, motion will be transmitted to the vertical shaft 66 and the drum 65 to exert a pulling force 95 on the belt 64.

Now, when the locking mechanism comprising the latch bar 60 and the catch 59 is in locking position, the loop chain core cutter will not be refracted when such pull is 100 exerted on the belt 64. The belt will be moved toward the position indicated by the dot and dash lines 64' in Fig. 1, and in doing so a bending force is exerted on substantially one-half of the crescent-shaped mass of coal 105 dislodged, with the effect of breaking up the same into smaller sections, as indicated by the irregular dot and dash lines 56, 57 and 58. It should also be observed that as the material is broken up into smaller sections it is moved wholly or partially over on to the forward arcuate end of the platform 10. The forward edge of the platform is indicated by the full line 70' in Fig. 1.

110 Rigidly connected to the frame 21 are 115 the arms 71 which extend radially as shown in Fig. 1, to constitute a spider having the frame 21 at its hub. Secured to the outer ends of the arm 71 is an upright cylinder 74 which is adapted to act as a fulcrum to secure the necessary bending force for breaking up the crescent-shaped mass of coal into 120 smaller sections when such mass is wrapped around this abutment by the pull exerted on the belt 64. It will be observed that the 125 spider arms 71 may be so located or arranged with respect to the loop chain core cutter that when the latter is locked in position one of the radial arms 71 will project directly forward as shown in Fig. 1, to form a 130

strong abutment. However, the cylindrical drum 74 may itself be made of sufficient strength to act as a fulcrum on which to break up the crescent-shaped mass of dislodged material into smaller sections.

In order to move the material onto the platform in such position that the conveyor flights 19 will move the material toward loading position, the lever 60 is lifted after substantially half of the crescent-shaped mass of material has been wrapped around the drum 74, as shown by the dot and dash lines in Fig. 1. When the locking mechanism is released by the lifting of the lever 60 and the rotation of the drum 65 is continued, the loop chain core cutter will be gradually pulled around to its initial position. As this occurs the drum 74, being rigidly secured to the arms 71, will rotate with the core cutter. The return of the drum 74 is therefore dependent upon the return movement of the loop chain core cutter. The smaller sections of the material will be held in contact with the peripheral portion of the drum 74 and move with the same, it not being required for the material to slide over the drum while being pressed against it. While the loop chain core cutter is being retracted the other half of the crescent-shaped mass of coal will also be broken up into smaller sections and then advanced toward the flight conveyor, where such sections will drop into the trough 75 and be moved by the laterally projecting flights 19 toward the rear end of the platform 10. A guide plate 76 may be provided in suitable position to direct the material away from the drum 74 and into proper position with respect to the flight conveyor.

In practice I prefer to design and operate the machine in such a manner that two crescent-shaped masses of coal between the roof and the floor of the mine will be cut out during each arcuate feeding movement of the loop chain core cutter across the face of the mine wall, particularly when the material is quite hard and not easily broken into smaller sections for transfer to the conveyor. I therefore provide a horizontal plane kerf cutter 100 for dividing the core cut by the core cutter into two sections 101 and 102, as shown in Fig. 2. However, when the material is of such nature that it is easily broken, the dividing cutter 100 may be omitted. In that event I prefer to operate the machine in such manner that two sections of crescent-shaped material between the floor and the roof of the mine will be sufficient before the machine must be moved forwardly to a new position. I prefer also to slice out the upper section first in order that the bottom of the horizontal kerf may act as a shelf for the cuttings produced by the loop chain core cutter. When these cuttings are ejected the forward lip 70' of the platform should be

in position to receive the same. The chain 32 being operated in the direction of the arrow 44, will cause the cuttings to be moved over the inclined surface 77 on to the platform from which they can readily be scraped into the trough 75 to be acted upon by the conveyor flights 19.

The forward lip 70' is adjustable longitudinally because it in reality forms a part of a supplemental platform 10', fitting in suitable grooves or guideways in the main platform 10. By means of a lever 78 pivoted to the supplemental frame at 79 and having a pin and slot connection 80 to the supplemental platform 10', the latter may be moved forwardly or backwardly at will. In this manner the position of the lip 70' may be adjusted with respect to the mine wall and the lower horizontal kerf.

In order to adjust the loop chain core cutter to the desired elevation for making a core cut across the mine wall, I provide mechanism for lifting and lowering the supplemental frame on the pivots 5. At one side of the main frame and connected rigidly to one of the vertical standards 6 is a forwardly extending bracket 81, the forward end of which is provided with an opening through which extends a screw-threaded rod 82, the lower end of which is pivoted at 83 to a bracket fixed to the platform 10, and extending laterally therefrom as indicated at 84 in Fig. 1.

By turning the wheel 85 which is screw-threaded onto the rod 82 the supplemental frame may be tilted on the pivots 5 and the loop chain core cutter and all parts associated therewith can thus be adjusted in elevation. For instance, the loop chain core cutter can be moved into position for making a cut across the upper portion of the mine wall, or into position for making a cut across the lower portion of the mine wall.

In order to shorten the width of the mining machine and enable the same to pass through narrower entries, the supplemental platform 10' may have a section thereof, such as that indicated by the reference character 10" in Fig. 1, provided with hinges 86, 86, which will enable the section 10" to be folded upwardly and over against the cylinder 74 when the loop chain core cutter is in the position illustrated in Fig. 2.

As before stated, when the material to be mined is so hard that it is difficult to break it up into smaller sections for loading, I prefer to add the horizontal plane kerf cutter shown at 100 in Figs. 1 and 2. This kerf cutter 100 and the means for operating it constitute a self-contained mining device 125 mounted on the plate 103 which is adapted to be detachably connected at 104 to one of the radial arms 71, as shown in Fig. 1. This self-contained mining device may be inserted through the opening 105 in the cylinder 74, 130

as shown in Figs. 1 and 8. This self-contained mining device is shown in elevation in Fig. 3, and in plan in Fig. 4. It should also be understood that the mining device 5 shown in Figs. 3 and 4 is detachably connected in its entirety to the plate 103 at 106, 106, as shown in Fig. 1, lateral spaced apart perforated lugs 106' being provided for this purpose.

10 The plane kerf cutter which is adapted to divide the crescent-shaped mass of coal cut out by the loop chain core cutter, comprises a circular cutter support 107 which is detachably connected by means of bolts 108, 15 108' and nuts 109, 109', to the housing 110, as shown in Figs. 3 and 4. On the periphery of the circular cutter support 107 is mounted the cutter frame ring 111, which is provided with a series of bit sockets with cutting tools 20 100' therein, as shown in Figs. 3, 4 and 7.

In order to drive the ring cutter a series of openings 112 is provided in the ring 111, in position to receive the teeth 113 of a sprocket 114 mounted in the housing 110, as 25 shown in Fig. 4.

Secured to the end plate 110 is a casing 115, as shown in Figs. 3 and 4. The casing 115 may be detachably connected to the plate 110 by means of cap screws 116. It 30 should be noted that the cutter support 107 is secured to the plate 110 and the casing 115 is rigidly secured to the plate 103, which in turn is rigidly secured to one of the arms 71, as shown in Fig. 1. The casing 115, together with the plate 110, entirely encloses the sprocket wheel 114 and the gearing for transmitting power thereto. The teeth 113 project through the bottom of one end portion of the casing 115, as shown in Fig. 3, 40 in position to mesh with the spaced apart openings 112 in the ring 111.

In order to rotate the power transmission gearing within the casing 115, a motor 117 is mounted as shown in Figs. 3 and 4. Preferably this motor 117 is an electric motor 45 provided with a frame having bracket arms 118, which can be detachably connected to the casing 115 by means of cap screws 119. A coupling is provided at 120 to connect the 50 motor shaft to the shaft 121. By means of this construction the motor may be removed and substituted or replaced by another according to the condition of the material upon which the plane kerf cutter is to operate.

The shaft 121 is keyed to the inner hollow frame 122 which carries a bearing for the 55 shaft 123, which is spaced radially from the shaft 121, as shown in Fig. 4. The shaft 121 is extended loosely through the journal bearing 124, which is keyed at 125 to the casing 115. A stationary gear 126 extends 60 around the journal bearing 124 on the inside of the casing 115, in position to mesh with 65 the gear 127, which is secured to one end of

the shaft 123. Secured to the other end of the shaft 123 is another gear 128, which meshes with the gear 129 on hub 130 of the sprocket wheel 114.

The inner end of the shaft 121 is of reduced diameter, as shown at 131 in Fig. 4, and extends into the journal bearing 132, which is supported by the plate 110 and secured to the latter by means of the cap screw 133. It should be noted that the hub 75 130 is keyed to the sprocket wheel 114, but is mounted loosely on the bearing 132. The latter therefore serves as a bearing for the sprocket wheel 114, together with the gear 129, and also as a bearing for the inner reduced end 131 of the shaft 121. The hub 130 fits between the collar 134 of the bearing 132, and the plate 110. That portion of the bearing 132 which extends through the plate 110 is of reduced diameter to form a 80 shoulder to fit against the inner side of the plate 110, so that the cap screw 133 may secure the bearing 132 rigidly to the plate 110.

The gearing in the casing 115 is differential to secure rotation of the sprocket wheel 114. This may be done by providing the gear 129 with more or less teeth than the gear 128. For instance, if the gear 128 is provided with one more tooth than the gear 95 129, the latter will be rotated one tooth each time the gear 128 makes a complete revolution around the axis of the gear 129. It should be understood that when the motor 117 rotates the shaft 121 the inner casing 122 100 will be rotated, thus causing the shaft 123 to revolve around the shaft 121. The gear 126 being held stationary relative to the frame 115 will cause the shaft 123 to be rotated by reason of the gear 127 meshing with 105 the gear 126. But the gear 128 also tends to walk around the gear 129, and since the gears 128 and 129 have a different number of teeth a differential movement will be obtained so as to secure rotation of the 110 sprocket 114 in the proper direction to rotate ring cutter 111 in a clockwise direction, as viewed in plan in Fig. 4. If the direction of rotation of the ring cutter is not proper for effecting cutting, the motor 117 may be reversed to secure the desired 115 direction of rotation of the cutter. A high speed motor 117 may be used because the gearing in the casing 115 is reduction gearing which will secure the desired comparatively slow feeding movement of the ring cutter in conformance with the speed of feeding movement of the loop chain core cutter. The motor 117 being an electric motor, it may readily be controlled as to 120 speed as well as direction of rotation to secure the desired speed of feeding movement of the ring cutter.

It should be particularly noted that, as shown in Figs. 4 and 5, the gears 127 and 128

128 are entirely enclosed not only within the casing 115 but also within the frame 122. An accurate balance for the gears 127, 128 and the shaft 123 may thus be secured relative to the axis of rotation of the frame 122. Furthermore, the gears 127 and 128 are not exposed to the air or atmosphere in such manner as to act as fans and thus tend to consume power of the motor.

10 It will thus be seen that both the balancing of the gears 127, 128, and the confining thereof so that they will not act as fans render the power transmission mechanism more efficient than it would be if the frame 122 were not used.

15 The ring cutter 111 is provided with an inner peripheral groove 135 and the circular support 107 is provided with a similar groove 136 to receive the balls 137 which 20 are mounted in a ring cage 138. As shown in Figs. 9 and 10, this ring cage 138 may be composed of a ring of metal through which holes 139 are bored radially to form partitions 140. When the ring cutter 111 is to

25 be assembled on the circular support 107 an opening 141 is drilled into the periphery of the support 107 and another hole is drilled through the lateral face of the support 107, so as to communicate at 142 with the opening 141. A ring plate 143 is placed in the 30 position shown in Fig. 6 and the ring 111 is placed over the ring plate 143, a gasket being located at 144, which gasket fits into a circular groove on the lower side of the

35 ring 111. The ring plate 143 fits into a circular groove on the bottom of the support 107 so that the bottom surface of the ring plate 143 will be flush with the bottom surface of the support 107. Now, with the 40 plate 145 still removed with the ball bearing cage 138 may be placed on top of the plate 143 with none of the balls, as yet, in position. With the block 146 and the rivet 147 removed, or not as yet in position, the

45 balls may be passed through the opening 142 into the space 141 and inserted one after another into the openings 139 in the ball bearing cage 138. After all of the balls have been inserted into the cage 138 the 50 block 146 may be placed in the position shown in Fig. 6, so as to establish continuity of the ball bearing raceway 135, in the periphery of the support 107. The plate 145 may then be placed in position with the gasket 148 fitting in a circular groove on the upper side of the ring 111. The plate 145 is connected to the frame 107 so as to have its upper surface flush with the upper surface of the ring 111, and also flush with the

55 outer upper surface of the support 107. A portion of the support 107 is cut away as illustrated at 149 to lessen the amount of material used in the support 107. After the 60 plate 145 has been secured in position the various parts which have been assembled

may be secured in adjusted relation by means of a series of spaced apart rivets 147, as shown in Figs. 4 and 6.

Before the parts shown in Fig. 6 have been assembled a suitable lubricant may be 70 introduced into the circular chamber through which the balls 137 move. It should be noted that the joints 150 and 151 between the plates 145, 143 and the ring 111 are 75 farther away from the center of rotation than the center of the ball bearing cage. The plates 145 and 143 are riveted at 147 to the periphery of the support 107 inside of the ball bearing cage, thus securing a liquid-tight joint between these plates and the 80 peripheral portion of the ring support 107. No dirt or foreign material can be drawn into the ball bearing by reason of the centrifugal action thereof; on the contrary, the tendency of such centrifugal action is to 85 throw out the heavier particles of foreign material through the joints 150 and 151.

The cutter bits 100' may be secured in the bit sockets 152 by means of the set screws 153 as shown in Fig. 7. Preferably, an 90 opening extends entirely across the ring 111, as indicated at 154 in Figs. 4 and 7. In this manner a surface 155 is provided for the rear side of the cutter shank 156, and a bearing face 157 is also provided for the 95 triangular portion of the cutting tool, as shown in Figs. 4 and 7. Preferably, a notch 158 is reserved for the neck 159 of the cutter bit, as shown in Fig. 7. The cutter bits may then be re-sharpened when they 100 become dull, and reformed so that their cutting points will remain approximately equidistant from the center of the ring 111, and whenever the bits are reformed they may be shaped so as to rest against the surfaces 155 105 and 157, without extreme accuracy being necessary as to the neck 159, which may be located at the notch 158.

110 Slots 160 are extended transversely through the ring 111 at the inner ends of the bit sockets. Such openings 160 facilitate cleaning of the bit sockets when the bits are to be inserted and also facilitate loosening the bits when they are to be removed.

115 As shown in Fig. 1, the plane kerf cutter 100 is mounted on the rotating frame 21 so as to be fed with the loop chain kerf cutter. The plane kerf cutter 100 is mounted in position to cut a horizontal kerf in advance 120 of the loop chain core cutter, but when the complete crescent-shaped mass of material comprising the upper and lower sections 101 and 102 has been cut out from the mine wall, such mass will be divided partially or 125 completely by the horizontal kerf cut by the kerf cutter 100. The belt 64 is of sufficient height to grasp both of the sections 101 and 102 when the loop chain kerf core cutter is held in the position shown in Fig. 1 and 130

a pull exerted on the belt 64. If the horizontal kerf cutter 100 has partially separated the crescent-shaped mass, the pull exerted on the belt 64 will complete the work and both sections 101 and 102 will be broken into smaller sections as indicated by the dot and dash lines 56, 57 and 58.

In the operation of the machine the motor 117 is started so as to rotate the plane kerf-cutter 100 in a clockwise direction as viewed in plan in Fig. 1. The cutting apparatus is assumed to have been previously adjusted to its proper inclination for the production of a core cut across the mine wall, this being effected by the operation of the wheel 85. Before the cutting operation is begun, the loop chain kerf-cutter should be extended diametrically opposite the position shown in Fig. 1. When the cutter-frame is in this initial position, the entire machine will be moved forward into a new position and held in such adjusted position by means of the roof jacks 8, 8. During the normal operation of the machine, the loop chain core cutter will be in the said initial position with the plane kerf cutter 100 in advance thereof when the cutting apparatus is to be readjusted vertically or both vertically and forwardly. Inasmuch as the core cutter frame 33 may have sufficient width to act as a shelf or carrier for the material cut out, it will hold up its end of the cut out crescent-shaped mass of coal until ready to be broken into smaller sections and moved onto the platform 10'. If any material remains on the inner lower surface of the cutter frame 33 or on surface of cutter frame 107, it will be forced off the same and onto the platform 10' inside of the belt 64 as soon as the new cut is begun.

When the machine is in readiness for the cutting to begin, the clutch 38 is thrown in to effect the operation of the flight conveyer and of the gears 26, 27, 28 and 29, which are connected to the sprocket wheel 31 and the chain 32 to drive the latter in the direction of the arrow 44. At the same time or immediately thereafter, the clutch 51 is thrown in to effect a pull on the rope 47 and the gradual feeding forward of the cutter frames 33 and 107 through an arc of about 180°, while the chain cutter is being driven and while the ring cutter is being rotated. When the cutter frames 33 and 107 reach their limiting positions, they will be automatically locked against retraction by the latch mechanism comprising the lever 60.

An entire crescent-shaped mass having been cut from the mine wall and divided by the plane kerf cutter 100 into two sections 101 and 102, the clutch 51 is thrown out and the clutch 69 thrown in. A pull on the belt 64 will then be exerted to break up into smaller pieces the sections 101 and 102 just cut away from the mine wall. In doing this,

the smaller sections of coal will be moved partly or wholly onto the platform 10' and wrapped around the drum 74. As soon as this occurs, the lever 60 is lifted to release the latch mechanism whereupon the pull on the belt 64 will start the cutter frames 33 and 107 on their return paths to restore them to their initial positions. During the retraction of the cutter frames 33 and 107, the remaining portions of the crescent-shaped sections 101 and 102 will be broken into smaller pieces and substantially all of the material will be carried into position to be acted upon by the flights 19. Because the cutter 100 acts in advance of the core cutter, there is little or no tendency for any dislodged material to remain on the cutter frame 107 after the loading operation has been completed.

During the retraction of the cutter frames 33 and 107, the spider frame with the cylindrical drum 74 permanently secured thereto will also be rotated in a clockwise direction. After the core material has been wrapped against the drum 74, rotation of the latter assists the belt 64 in directing the dislodged material to the curved wall 76 and into the trough 75 of the conveyer.

By making a crescent shaped sectional cut, in the upper portion of the mine wall first, and then a similar cut immediately below the same, advantage may be taken of the lower surface of the horizontal kerf cut by the core cutter, as a ledge or shelf from which the cuttings may be scraped by the chains onto the platform 10'' from which they may be moved by the belt 64 and the flight conveyer 18, 19. Whenever desired, the forward lip 70' of the supplemental platform 10' may be adjusted in position by operating the lever 78.

By providing an additional catch 87 inclined on its upper surface and having a vertical face to prevent retraction of the cutter frame, and locating this additional catch in the position indicated in Fig. 1, the cut sections of core material may be moved through short arcs. This may be done by releasing lever 60 from the catch 59 when the clutch 69 is first thrown in to exert a pull on the belt 64. As soon as the lever 60 is released from the latch 59, it may be allowed to engage the catch 87 when the latter has rotated a sufficient distance. The catch 87 will then be relied upon to hold the cutter frames 33 and 107 stationary while the pull on the belt 64 continues and while it is being moved to the position shown by the dot and dash lines shown in Fig. 1 to break up the crescent shaped sections 101 and 102 into smaller sections.

It should be understood that that portion of the mining machine shown in the drawings as operating on the face of the mine wall may be regarded as the front of the

mining machine. The operator may control all the operations from the rear of the mining machine because devices well known in the art may be provided for operating 5 the lever 78, the wheel 85, the lever 60, and the electric switches and controllers for controlling the electric motors 9 and 117, from a suitable location back of the mining machine. By providing the flange at the lower 10 portion of the drum 65 with a series of notches 88, this drum may be held from rotation by the pawl 89, which is pivoted at 90 to the supplemental frame. In this way, the drum 65 may be locked against rotation 15 in either direction. When the clutch 69 is released and the pawl 89 moved into one of the notches 88, the drum 65 will be locked while the other end of the belt 64 may continue to move with the cutter-frames 33 and 20 107. The continued movement of the cutter frame 33 may, therefore, be relied upon when desired for breaking up the sections cut out even before the same are entirely severed from the mine wall. If the drum 65 25 is locked at the proper time, the belt 64 will reach the position shown by the dot and dash lines 64' in Fig. 1, when the cutter frames reach the full line positions shown in Fig. 1. It is also contemplated to operate the 30 winding drum 65 to move the belt 64 to its dot and dash line position 64' while the cutter-frames are advancing, thereby breaking up the sections 101 and 102 by prying them from the mine wall while still integral 35 therewith, or before any section is entirely severed by the cutting mechanism. These operations of locking the drum and also, when desired, operating the drum when the cutting mechanism is being fed, will increase 40 the efficiency of the apparatus by enabling the cutting mechanism to be restored to initial position soon after it makes a complete feeding movement.

It should be noted that the cutter frame 45 33, when in adjusted position, is rigidly connected to the frame 21 which constitutes the upright axle on an upright axis. The cutter-frame 107 is also rigidly connected to the frame 21 and the ring-cutter 111 is always in position to cut a kerf which extends 50 in a plane at right angles to the axis of swinging feeding movement of the loop chain core cutter. When the wheel 85 is rotated to tilt the core cutter on the horizontal axis 5, the vertical axis of swinging movement of the core cutter will be tilted so as 55 to incline from the forward portion upward and rearwardly. At the same time, the axis of rotation of the ring cutter 111 will be tilted so as to remain in parallelism with the axis of swinging feeding movement of the core cutter. When the core cutter is 60 swung to its upper position, it is enabled to make an arch-shaped cut along the mine 65 roof, which forms a support for the roof

and enables the chamber to be cut without the use of props. In this way a self-supporting chamber having an arch-shaped roof which remains intact for a long period of time is produced. This arching of the roof 70 is particularly desirable when there are strata of foreign material in the vein of coal somewhere between the floor and roof of the mine chamber. In that event, the plane kerf-cutter 100 may be positioned so as to act 75 on the stratum of foreign material to cut it out and permit the cuttings of the foreign material to be deposited in the trough 75 for removal independently of the removal 80 of the coal. By referring to Fig. 1 it will be seen that the inner side of the kerf-cutter 100 extends to the trough 75 so that during the action of the plane kerf-cutter on the stratum of foreign material, the cutter will throw the foreign material into the trough 85 75 for removal by the flight conveyers before the coal is broken down and moved onto the conveyer. It should also be noted that notwithstanding the formation of the arch-shaped roof by the core cutter, the plane 90 kerf-cutter may nevertheless be used to cut the sections 101 and 102 since the axis of rotation of the cutter 111 always remains parallel to the axis of feeding movement of the core cutter. 95

Obviously those skilled in the art may make various changes in the details and arrangement of parts without departing from the spirit and scope of my invention as defined by the claims hereto appended, and it 100 is therefore desired not to be restricted to the precise construction herein disclosed.

Having thus fully described an embodiment of my invention, what I claim and desire to secure by Letters Patent of the 105 United States, is:

1. In a mining machine, the combination with a frame, of mechanism having an unobstructed core opening therethrough and mounted on said frame for entirely cutting 110 from a mine wall a crescent-shaped mass of material in a general horizontal direction, of additional cutting mechanism for dividing such crescent-shaped mass into sections extending in a general horizontal direction, 115 and means mounted on said frame near said cutting mechanism for effecting mechanically the transfer of all of the dislodged mass of material in its solid state in large blocks from its cut position in the mine wall 120 toward loading position.

2. A mining and loading machine comprising a supporting frame, a loop chain core cutter mounted on said frame, means for operating said loop chain core cutter to 125 cut a core of material in a mine wall, additional cutting mechanism for cutting a kerf along the core, and means mounted on said frame and extending therefrom into position for acting on the core in its cut posi- 130

tion at the mine wall to move all of it directly away therefrom along said frame toward loading position.

3. A mining and loading machine comprising a supporting frame, a loop chain core cutter mounted thereon, means for operating said cutter to cut a core mass of material in its native bed, additional cutting mechanism for cutting a kerf along the core mass longitudinally thereof, and power mechanism mounted on said frame and extending into position for taking substantially all of the cut material from the space assumed thereby after being cut and moving the same back from the unmined mass along said frame toward loading position.

4. A mining and loading machine comprising kerf-cutting mechanism including a divider for cutting from a mine wall a predetermined mass of material, and means operable in a mine chamber between the floor and roof thereof for moving the entire mass of severed material from the position assumed thereby after being dislodged from the mine wall, in a general horizontal direction along said mine chamber toward loading position.

5. A mining and loading machine comprising a supporting frame, a loop chain core cutter mounted on said frame to extend out from the same, means for operating said cutter to cut a core mass of material in the mine wall, a plane kerf cutter mounted on said frame in position to cut a kerf in a plane intersecting the space within the boundary of said core cutter, and power mechanism mounted on said frame to follow said core cutter in position to act on the material in whatever condition it assumes of itself immediately after being cut, to take substantially all of it from a mine wall along said frame toward loading position.

6. A mining and loading machine comprising a supporting frame, a core-cutting mechanism having an unobstructed core opening therethrough and mounted on said frame for movement relatively thereto, and dislodging mechanism mounted in predetermined relation to said core-cutting mechanism and comprising a plane kerf-cutter also movable relatively to said frame for acting on the material in its cut position in the mine wall and moving it directly therefrom toward loading position.

7. A mining and loading machine comprising a supporting frame, mechanism mounted on said frame for cutting a core by cutting on both sides of a body of material in a mine wall and at the back thereof, a plane kerf-cutter mounted on said frame in position to cut a kerf longitudinally of said core between said sides thereof, and manually controlled power mechanism mounted on

said frame adjacent said core cutting mechanism for effecting mechanically the transfer of the cut material from its cut position in the mine wall toward loading position independently of the operation of said core-cutting mechanism.

8. A mining and loading machine comprising a supporting frame, an endless chain cutter, a chain cutter frame for said cutter and enclosing an open space bounded in front and at the top and bottom by said chain cutter to guide the latter, means mounted on said frame for operating said chain cutter by actuating the same relatively to said guide frame and moving the latter to feed said chain cutter transversely to produce kerfs in a mine wall above and below and at the back of a body of material while the latter remains in its native position, means for producing a dividing kerf longitudinally of such body of material, means mounted on said frame and extending therefrom for breaking up the cut material extending through said guide frame, mechanism mounted on said supporting frame for receiving the broken up material, and mechanism for transferring the broken material toward loading position.

9. In a mining machine, the combination with a supporting frame, of core-cutting mechanism mounted thereon, a kerf-cutter and power operating means for the same forming a detachable self-contained unit mounted on said frame in position to effect the cutting of a kerf longitudinally of the core cut by said core-cutting mechanism.

10. In a coal mining machine, the combination with a supporting frame, of a loop chain core cutter having an unobstructed core-opening therethrough and having one of its runs in position to cut a plane kerf, a separate cutter for cutting a kerf in a plane extending through said unobstructed opening and parallel to said first named plane kerf, means for operating said loop chain core cutter and said separate cutter including the feed thereof, and means for adjusting the position of said core cutter and said separate cutter while maintaining the aforesaid relation of the plane kerf cut thereby.

11. In a coal mining machine, the combination with a main frame, of a supplemental frame pivoted to said main frame, an upright chain cutter carried by said supplemental frame and having upper and lower runs rectilinear in elevation, means for operating said chain cutter including feeding movement thereof laterally relatively to said supplemental frame during the cutting operation to produce a core having upper and lower flat surfaces along such rectilinear portions of said cutter, an additional cutter for cutting a plane kerf along the core between said flat surfaces, and means for adjusting

the inclination of said supplemental frames relatively to said main frame to move both of said cutters to various elevations.

12. A mining and loading machine comprising supporting framework, means mounted thereon for cutting spaced-apart kerfs and a back intermediate kerf bounding a core of material in a mine wall, conveyer mechanism mounted on said framework to have a predetermined relation thereto and to said cutting means, an additional kerf-cutter for slotting the core longitudinally, and mechanism mounted on said framework intermediate said first-named cutting means and said conveyer mechanism for taking the dislodged material at various heights directly from the space originally occupied thereby in its native bed and moving such material onto said conveyer mechanism.
13. In a mining machine, the combination with a supporting frame, of loop chain core cutting mechanism mounted to swing on an upright axis on the forward portion of said frame, a plane kerf-cutter for cutting a kerf in a plane extending through said core cutting mechanism between spaced-apart runs thereof, means for operating said core-cutting mechanism and said plane kerf-cutter including the swinging of both on said upright axis relatively to said supporting frame while the latter remains stationary, and means for adjusting the elevation of the entire core-cutting mechanism and said plane kerf-cutter to predetermine the elevation of the core to be cut in a mine wall.

14. In a mining machine, the combination with a supporting frame, of core-cutting mechanism mounted thereon and having an unobstructed core-opening therethrough and a flat kerf-cutter in position for cutting a kerf in a plane extending through such opening and completely through the core cut by said core-cutting mechanism, said flat kerf-cutter being capable of cutting a kerf of greater depth than its radius, and means for operating said core-cutting mechanism and said flat kerf-cutter to effect the cutting of a plurality of cores.

15. In a mining machine, the combination with a supporting frame, of multiple core-cutting mechanism mounted thereon and comprising a loop chain core cutter having a core opening extending therethrough and a flat kerf-cutter in position to cut a kerf in a plane extending through said opening and completely through the core, and means for operating said multiple core-cutting mechanism including feed of both said loop chain core-cutter and said plane kerf cutter to effect the cutting of a plurality of cores.

16. In a mining machine, the combination with a loop chain core cutter having upper and lower spaced-apart runs rectilinear in elevation, said core cutter having

an unobstructed core opening therethrough, means for operating said loop-chain core cutter including feed thereof laterally, a plane kerf-cutter for cutting a kerf in a plane extending through said opening, and means for adjusting the position of the entire chain cutter including such rectilinear portions to enable successive cuts to be made across the mine wall at various elevations in a coal mine while said plane kerf-cutter remains in position to cut a kerf extending through said opening.

17. In a mining machine, the combination with a main frame, of a supplemental frame adjustably mounted on said main frame, a hub mounted on said supplemental frame to have an upright axis of rotation, a cutter frame extending radially from said hub and having an unobstructed core opening at its outer portion, an endless loop-chain cutter mounted on said cutter frame, another cutter frame extending radially from said hub, cutting mechanism mounted on said last-named cutter frame in position to cut a kerf in a plane intersecting said upright axis, means for operating said chain cutter and said cutting mechanism including feed thereof by lateral movement together with said hub on the upright axis of the latter, and means for adjusting the elevation of said supplemental frame relatively to said main frame to vary the height of said hub together with both of said cutter frames.

18. In a mining machine, the combination with a supporting frame, of a hub mounted on bearings on said frame, a cutter frame rigidly connected to said hub and extending radially therefrom and having a core opening therethrough, a loop chain core cutter mounted on said cutter frame, means for partially rotating said hub together with said cutter frame to effect feeding of said chain cutter, means for driving said chain cutter to cause the same to travel along said cutter frame transversely to the direction of feed thereof, an additional cutter frame rigidly connected to said hub to move bodily therewith, and plane flat kerf-cutting mechanism mounted on said additional cutter frame in position to cut a kerf in a plane extending through the aforesaid core opening and completely through the core.

19. A mining machine comprising loop-chain kerf-cutting mechanism, a main frame, a supplemental frame on which said cutting mechanism is mounted to swing in feeding direction at right angles to the plane thereof, a plane kerf-cutter on said supplemental frame in position to cut a kerf in a plane intersecting the plane of said first-named cutting mechanism, and means for angularly adjusting the entire cutting mechanisms in the plane of the first-named cutting mechanism.

20. In a mining machine, the combination with a supporting frame, of a loop-chain core cutter mounted thereon, means for operating said loop-chain core cutter to cut a core mass of material, means for cutting simultaneously a kerf along such core mass between spaced-apart faces thereof, and power mechanism mounted on said frame for breaking up the core sections and moving the same back from the mine wall. 5

21. A mining and loading machine comprising mechanism for cutting a multiple core in its native bed between the floor and roof of a mine chamber, and means movable horizontally back from the mine wall along said chamber to draw the cut material with it for breaking loose such cut material and moving it toward loading position. 15

22. A mining machine comprising a supporting frame, multiple core cutting mechanism mounted thereon for simultaneously cutting spaced-apart kerfs and a back connecting kerf to form a column in a mine wall and an intermediate kerf to divide said column longitudinally, means for operating said cutting mechanism including the feed thereof to cut such column with its dividing kerf in a single operation along the mine wall, and means mounted on said frame and movable relatively thereto for breaking off pieces of the kerf-cut column and moving the same towards loading position. 30

23. In a mining machine, the combination with core-cutting mechanism, of plane kerf-cutting mechanism, arcuate feeding means for both of said cutting mechanisms, and means for removing substantially all of the cut material from the position assumed thereby after being dislodged along a path concentric with the arcuate feed of said cutting mechanisms. 40

24. In a mining machine, the combination with a loop-chain core cutter having a core opening extending therethrough, of means for driving said core cutter, a flat kerf-cutter in position to cut a kerf in a plane extending through said opening to cut entirely through the cut core, means for feeding both of said cutters, and means for removing substantially all of the cut material along the line of core-cutting feeding movement. 50

25. A mining machine comprising core-cutting mechanism have a core opening extending therethrough, a plane kerf-cutter for cutting a kerf in a plane extending through said opening, means for feeding said core-cutting mechanism and said plane kerf cutter over arcuate paths of travel, and means operating in the kerf produced by said core-cutting mechanism to move the cut material away from the mine wall independently of the feed of said core-cutting mechanism. 60

26. A mining machine comprising loop-

chain core-cutting mechanism, a frame, a cylinder mounted on said frame for movement circumferentially with said frame and with said cutting mechanism, a plane kerf-cutter on said frame and projecting through an opening in said cylinder, and means cooperating with said frame and with said cylinder for breaking up material cut out by said loop-chain core-cutting mechanism by moving the cut material directly from the mine wall against said cylinder. 70

27. In a mining machine, the combination with a loop chain core cutter having an unobstructed core-opening therethrough, of a frame for supporting said core cutter for swinging movement on an upright axis, a drum rigidly secured to said frame in position to interloop said core cutter and in position for the cuttings from the core cutter to move under said drum toward said upright axis, and mechanism cooperating with said drum for breaking up the material cut out by said core cutter. 80

28. A mining machine comprising a supporting frame, a swinging frame pivoted thereto and having a spider arm hub, a loop-chain core cutter mounted on said hub, and a plane kerf-cutter mounted on said hub to move bodily therewith. 85

29. In a mining machine, the combination with core-cutting mechanism, of a plane kerf-cutter for cutting a kerf in a plane extending through said core-cutting mechanism, means for operating said core cutting mechanism and said kerf-cutter to effect the dislodgment of a divided crescent-shaped mass of material from the mine wall, and flexible means connected to said core-cutting mechanism in position to engage the dislodged material and move the same back from the mine wall. 95

30. A mining machine comprising a supporting frame, kerf-cutting mechanism for cutting spaced-apart upper and lower kerfs and an upright back kerf communicating with each other to cut a core in a mine wall leaving the forward end thereof integral with such mine wall, means for cutting a dividing kerf along such core, and mechanism mounted on said frame and extending therefrom in position to penetrate the vertical kerf and break the divided portions of the core from the unmined mass. 110

31. In a mining machine, the combination with a supporting frame, of core-cutting mechanism mounted thereon, means for operating said core-cutting mechanism, and a flat kerf-cutter in position to cut a plane kerf longitudinally of and completely through the core cut by said core-cutting mechanism, said flat kerf-cutter being capable of cutting a kerf of greater depth than its radius. 120

32. In a mining machine, the combination with a supporting frame, of a loop chain

core-cutter having an unobstructed core-opening therethrough, means for operating said core-cutter, and a flat kerf-cutter in position to cut a plane kerf longitudinally of the core cut by said core-cutter and completely through such core, said flat kerf-cutter being capable of cutting a kerf of greater depth than its radius.

33. In a mining machine, the combination with a supporting frame, of core-cutting mechanism mounted thereon for arcuate swinging feeding movement, a flat kerf-cutter mounted on said frame to have an arcuate swinging feeding movement in position to cut a plane kerf longitudinally of the core and completely through the same, said flat kerf-cutter being capable of cutting a kerf of greater depth than its radius, and means for operating said core-cutting mechanism and said flat kerf-cutter to effect the cutting of such core and the cutting of such longitudinal kerf.

34. In a mining machine, the combination with a supporting frame, of core-cutting mechanism mounted thereon, a self-contained power-operated kerf-cutter mounted on said frame in position to effect the cutting of a kerf longitudinally of the core cut by said core-cutting mechanism, said

kerf-cutter being capable of cutting a kerf of greater depth than its radius, and means for operating said core-cutting mechanism to drive the same independently of the drive of said kerf-cutter whereby the driving of the kerf-cutter may be regulated in accordance with the feed independently of the regulation of the drive of the core-cutting mechanism.

35. In a mining machine, the combination with a supporting frame, of core-cutting mechanism mounted thereon for arcuate swinging movement on an upright axis, a flat kerf-cutter mounted on said frame to have an arcuate swinging feeding movement in position to cut a plane kerf longitudinally of the core and completely through the same, said flat kerf-cutter being capable of cutting a kerf of greater depth than its radius, and means for operating said core-cutting mechanism and said flat kerf-cutter to effect the cutting of such core along the face of the mine vein and the cutting of such longitudinal kerf.

In testimony whereof I have signed my name to this specification on this 18th day of November, 1922.

EDMUND C. MORGAN.
